CUTTING-OFF TOOL

Dalmar Templeton Brownlee, Indianapolis, Ind.

Application December 31, 1941, Serial No. 425,247

6 Claims. (Cl. 29—101)

This invention relates to an improved tool of the variety which is used in lathes, screw machines and the like for cutting off pieces from bars of steel and other material.

In use the tool is secured to a cross slide or swinging arm of the machine and slowly fed into a rotating bar of the material from which a piece is to be cut off.

Such tools are commonly known as cutting off tools and their performance is relatively unsatisfactory. As commonly constructed they are quite fragile and must be carefully handled and frequently sharpened; otherwise the cut will be rough and the tool may seize and be broken.

The usual cutting off tool consists of a holder provided with a slot and clamping means to secure a straight blade. The blade is usually a relatively long and thin bar of high speed steel, either rectangular or keystone shaped in cross section. The portion of the blade that does the cutting protrudes from the holder and is commonly ground so as to obtain relief on the sides and a lip or chip curler on the top edge. In relieving, the blade is ground so as to taper on both sides from the cutting edge back to the holder and if the blade is of rectangular cross section the grinding must also reduce the thickness from top to bottom. This leaves the cutting edge of the blade thicker than the rest of the protruding portion and eliminates binding, but unfortunately brings the minimum cross section of the blade to the edge of the holder where the bending moment is greatest. As the end of the blade is ground off in sharpening the thickness of the entire relieved portion is gradually reduced as the relief must be run back a corresponding amount. Finally the area of the cross section of the blade at the edge of the holder becomes insufficient and either the relieved portion breaks off or is purposely broken off by the operator. Obviously a new cutting edge and relief must be ground on the blade.

In cutting off steel and certain alloys it is well known that a concave contour on top of the blade causes the chip to curl and shear off more easily, thereby prolonging the life of the cutting edge of the blade and reducing the load on both blade and machine. Tests have shown that this device, known as a chip curler or lip, may increase the amount of cutting as much as four times per 50 sharpening. However, each time a straight blade is sharpened the chip curler must be ground back further and deeper and soon the cross sectional area at the bottom of the chip curler becomes insufficient and either breaks at this point 55

or is broken off by the operator. A new cutting edge, chip curler and relief must be ground to restore blade to original condition. As the cross sectional area reduction due to relief grinding and chip curler grinding is additive, it will be readily understood why the number of sharpenings per blade is not large.

Altogether the use of straight cutting off blades is wasteful and expensive. Considerable time and skill are required to grind the proper relief and contour and in practical use more than one half is ground away, broken or scrapped. As high speed steel, the usual material for blades, is expensive and a serious shortage of this material appears near at hand, it is of utmost importance that this waste be eliminated.

It is an object of the invention to provide a cutting off tool that is economical in the use of high speed steel or other cutting material.

Another object of the invention is to provide a cutting off tool that may be quickly and correctly sharpened by a mechanic of limited experience.

Another object of the invention is to provide a cutting off tool that has an inherent chip curler.

Another object of the invention is to provide a cutting off tool that provides substantial support for the blade.

Other objects of the invention will appear from the following description taken in connection with the drawing, wherein I have illustrated a preferred embodiment of my invention, and in which:

Figure 1 is a side elevation of the complete tool.
Figure 2 is an end view of the holder without the blade.

Figure 3 is a side elevation of the blade.

Figure 4 is an end view thereof.

In the drawing the holder 10 is provided with a concave cylindrical blade seat 11 in which a number of small square teeth are cut. The blade 17 is in the form of an interrupted ring with teeth on its outer periphery matching those of the seat 11 in the holder. About midway of the seat 11 the holder is provided with a slot 12 that divides the seat into two portions and bifurcates the front end of the holder into two branches or arms. Perpendicular to the slot is a clamp screw 16 for the purpose of drawing the two portions of the seat 11 slightly closer together thereby securely holding the blade 17.

The holder 10 is recessed at 13 and 14 in order to reduce the thickness of the blade seat 11 to that of the thinnest part of the blade 17. The periphery of each of these recesses is that of a

circular arc scribed from a center located at the cutting edge 18 of the blade 17. The front end 15 of the holder 10 below the blade seat is sloped at an angle, preferably 10 degrees from the vertical, the purpose of which will be presently explained.

The blade 17 is keystone shaped in cross section from end to end with the thick end of the section inward and varies uniformly in average thickness from end to end, and has its greatest thickness at the cutting edge 18 and its least thickness at the point 19. While the entire blade may be made of one piece of high speed steel, for greater economy I prefer to make the major portion of the blade from inexpensive low carbon steel and braze thereto a relatively small piece 20 of high speed steel or other expensive cutting material. For economical manufacture I prefer to make up as complete rings and after tooth cutting and other machining operations, to cut each ring into two equal parts, each part constituting a blade.

In use the blade 17 is slipped into the holder 16 with a sidewise motion with the cutting end 21 protruding slightly from the holder and with the teeth on the blade interlocking those of the holder. The clamp screw 16 is now tightened to securely hold the blade. When sharpening is required the end 21 of the blade is brought up against the flat side of a grinding wheel at an angle, usually 10 degrees from the vertical. As a guide to correct sharpening the front end 15 of the holder is formed to this same angle. After several sharpenings the blade may be slipped out of the holder seat with a sidewise motion and rotated a tooth to advance the cutting edge to a new position for additional sharpenings. This may be repeated from time to time until the high speed steel piece 20 is almost entirely used up.

It will be observed that due to the construction of the blade and its mounting, a concave top surface for curling the chip is maintained throughout the life of the blade; that owing to its keystone cross section and lengthwise tapering thickness, the blade continues to have relief until it is used up; that the one simple operation of grinding the front end 21 of the blade parallel to the front end 15 of the holder assures the correct angle for the cutting edge; that the blade is well supported behind and below and thereby very resistant in use to deflection and breakage.

Although the invention has been described in connection with a tool suitable for use in an ordinary lathe, the shape and proportions of the tool and its parts may be greatly modified as conditions require. The invention therefore is to be limited only as indicated by the scope of the appended claims.

I claim:

1. A cutting off tool for lathes, screw machines and the like including a holder, a seat in the holder, a blade adapted to fit said seat, an arm 5 of the holder extending toward the cutting edge of said blade, recesses in one or both sides of the arm reducing the thickness thereof to approximately that of the blade with the periphery of said recesses approximating arcs of circles scribed from a center located near said cutting edge of the blade.

2. A cutting off tool for lathes, screw machines and the like including a holder, a concave seat in the holder, an interrupted ring shaped blade provided with a cutting edge and adapted to fit said seat, the thickness of the holder being reduced by recesses in one or both sides to approximately that of the thinnest part of the blade with the periphery of said recesses approximating arcs of circles scribed from a center located near said cutting edge of the blade.

3. A cutting off tool for lathes, screw machines and the like including a holder, a blade, a portion of the holder bifurcated into arms disposed in the plane of the blade, a seat in the arms adapted to hold the blade, with the thickness of the arms adjacent the blade not exceeding the thickness of the blade and means to clamp the arms and secure the blade in the seat.

4. A cutting off tool for lathes, screw machines and the like including a holder, an interrupted ring shaped blade, a portion of the holder bifurcated into arms, a concave seat in the arms adapted to hold the blade, the thickness of the arms adjacent the blade not exceeding the thickness of the blade and means to clamp the arms and secure the blade in the seat.

5. A cutting off tool for lathes, screw machines and the like, an interrupted ring shaped blade 40 with a toothed periphery, a portion of the holder bifurcated into arms, a toothed concave cylindrical seat in the arms adapted to fit the blade in meshing engagement, the thickness of the arms adjacent the blade not exceeding the thickness of the blade and means to pull the arms closer together and secure the blade in the seat.

6. A cutting off tool for lathes, screw machines and the like including a holder, a blade having an end inclined to form a cutting edge, a portion of the holder bifurcated into arms disposed in the plane of the blade, a seat in the arms adapted to hold the blade, the thickness of the arms adjacent the blade not exceeding the thickness of the blade, one arm extending to near said inclined end of the blade and terminating substantially parallel therewith and means to clamp the arms and secure the blade in the seat.
